JOSEPH LEOPOLD COYLE, OF LONDON, ONTARIO, CANADA, ASSIGNOR TO EPHRAIM BANNING, TRUSTEE, OF CHICAGO, ILLINOIS

FILLER FOR EGG CARTONS

Application filed June 19, 1928. Serial No. 286,538.

My invention relates to improvements in fillers for egg cartons, and the object of the invention is to devise a filler or other self-supporting egg carrier which will provide individual cushion support for the eggs, which will prevent breakage or pressure of one egg against another when a number of cartons or fillers are superposed, and which will hold the eggs in such position that the ends thereof will not press against any underlying eggs or objects with a consequent tendency to breakage. It is also an object to provide a filler which may be collapsed into compact form for the purpose of shipment, and which may be locked rigid when the filler is set up to receive the eggs so that the filler and the eggs contained therein may be readily lifted from the carton as if they were in a basket, and the self-supporting cellular egg holder, with the eggs suspended within the cells, may be placed in another carton, container, or the like, or within a show-case or refrigerator, as desired, and the invention consists essentially in the arrangement and construction of parts as hereinafter more particularly explained.

In the drawings:

Figure 1 is a perspective view of a carton partially broken away to exhibit the construction of my filler inserted therein;

30 Fig. 2 is a perspective view of the filler removed from the carton;

Fig. 3 is a transverse sectional view through the carton and filler and showing the position of the eggs therein;

35 Fig. 4, which is a perspective detail on a reduced scale of one of the transverse walls of the filler and a fragmentary portion of one of the longitudinal partitions, shows these parts in position ready to be interlocked;

40 Fig. 5 is a cross sectional view of an alternative construction;

Fig. 6 is a transverse section through a filler representing a further modified construction;

45 Fig. 7 is a plan view thereof, on reduced scale, illustrating the manner of its collapse;

Fig. 8 is a fragmentary perspective view of the filler construction shown in Fig. 6;

50 Fig. 9, which is a view similar to Fig. 6,

shows a further modification of the invention;

Fig. 10, which is also a view similar to Fig. 6, shows a still further modification of the invention;

55 Fig. 11 is a detail in section taken on line 11 of Fig. 10; and

Fig. 12 is a transverse section through a filler representing a still different modification in the construction.

60 In the drawings like characters of reference indicate corresponding parts in each figure.

Referring first to Figs. 1 to 4, inclusive, I have shown a carton 1 of conventional construction having its lid 1^x in the open position.

65 The filler comprises a series of parallel cross walls 3 formed of cardboard, or the like, each wall being provided centrally with an open ended slot 4 extending from the lower edge of the wall and centrally thereof vertically to a point intermediate of the height of the wall. The lower end of the slit is preferably chamfered off as indicated at 4^x to 70 permit of the easy insertion of a central longitudinal partition which engages therewith as will hereinafter appear.

75 I have provided also an opening 5 which is preferably rectangular and located above the upper end of the slot 4 and adjacent thereto so as to leave the transverse portion 5^x between the opening 5 and the slot 4. Extending from the lower edge of each wall 3 are

80 open ended slots 6 and 7 arranged adjacent to the end edges of the walls and of peculiar construction. The inner vertical wall of each of these slots is provided at its lower end with a ratchet tooth shaped projection 8. The op-

85 posing edge of the outer wall inclines upwardly and inwardly as indicated at 9 to a point above the upper end of the ratchet tooth 8 and then inclines outwardly in an opposite direction, as indicated at 10, to form a wide upper portion to each slot 6 and 7, the incline 90 of the edge 10 being directed to the upper end of the tooth 8 at the root. The upper edge 11 of the slot is preferably formed concentric 95

to this point.

In the filler assembly are certain longitudi-

55

65

70

75

80

85

90

95

95

100

nal partitions 12, 13 and 14 which connect the cross walls 3 together in spaced relation so as to form egg receiving cells. The central longitudinal partition 12 is provided with a series of open ended slots extending vertically down from the upper edge thereof, as indicated at 15. One edge of this vertical slot is provided with a ratchet tooth 16 and the opposite edge of the slot is preferably 10 curved around this tooth, as indicated by dotted lines in Fig. 1, the upper corners of the slot being chamfered off, as indicated at 17.

In order to interlock the cross walls and central longitudinal partitions, it is necessary merely to engage the slot 15 of the partition with the slot 4 of the cross wall until the tooth 16 springs into engagement with the opening 5, thereby locking the cross walls and central partition together. The connection thus provided is such that the cross walls may swing from their transverse position to a position parallel with the partitions when the filler is collapsed.

The outer partitions 13 and 14 are provided with notches 18 in their lower edge spaced apart to correspond with the distance between the cross walls. The side edges of these notches are preferably inclined inwardly. Slits 19 extend downward from the upper edge of these two partitions and in vertical central alignment with the notches 18 leaving therebetween an intermediate portion 20 of the body.

When the outer partitions 13 and 14 are engaged with the cross walls 3, the slits 19 are passed into engagement with the open ended slots 6 and 7 so that the intermediate portion 20 is carried above the ratchet tooth 8. When carried to this position, the upper end 40 edge of the notch 18 rests upon the upper horizontal edge of the tooth 8. Normally the partitions 13 and 14 are vertical and by means of their construction permit a swinging engagement with the cross walls 3 so that 45 when these walls are swung upon the central partitions 12, as previously described, the partitions 13 and 14 are carried in opposite longitudinal directions so as to be brought against the opposite faces of the central partition, thereby collapsing the filler into flat form making it convenient for shipment.

When it is desired to fill the filler with eggs, the outer partitions 13 and 14 are inclined outwardly from the position shown at the left hand side of Fig. 1 to the position at the right hand side thereof, and as shown in Figs. 2 and 3. By this swinging movement the notch 18 is carried from a position in alignment with the open ended slot 6 or 7 past the ratchet tooth 8 so as to extend at each side of the cross wall body, and thereby effectually prevent the swinging movement between the outer partitions and the cross walls as 60 previously described, and thereby preventing

collapse of the filler. The intermediate body portion 20 by this movement is carried into engagement with the inclined edge 10 of the slot 6 or 7 holding the partition 13 or 14 in an inclined position, and thereby producing 70 an egg receiving cell which is wide at the top and narrow at the bottom. When in this position, an egg indicated at 21 may be inserted in the cell formed by the cross walls and partitions 12 and 13 or 12 and 14, the sides of the egg engaging the central vertical partition and the inclined outer partitions, and thereby gripping the egg so that it cannot drop through the bottom of the filler as would be the case in ordinary constructions. 75

It will thus be seen that each egg 21 is resiliently supported upon the inclined partition 13 or 14, the upper edge of which bears against the adjacent longitudinal wall of the carton. Also by the inclination of the 85 side partitions, the point of an egg, as indicated at 21*, is carried inward so that the egg as a whole assumes an inward inclined position so that there is no danger of a pointed egg projecting downward through the 90 bottom of the cell so as to press against an egg contained in an underlying carton.

In Fig. 5 I have shown an alternative construction for the carton 22 in which is arranged a filler having cross walls 23 each formed with a central slot 25 and an opening 26, also a longitudinal partition 27, the slots 25, openings 26 and longitudinal partition 27 corresponding to the construction already described in connection with the remaining figures. In this form, however, the side slots 28 and 29 corresponding to the side slots 6 and 7 previously described, instead of being adjacent the outer vertical edge of the cross wall are formed adjacent the center of the wall, such slots being of the same general formation as the slots 6 and 7, but differing slightly in proportion. The outer partitions 30 and 31 also correspond in construction to the partitions 13 and 14, but instead of swinging to an upwardly and outwardly inclined position are permitted to swing to an outwardly and downwardly inclined position extending from the central longitudinal partition 27 downwardly towards each outer wall of the carton. By this means a resilient support for the eggs is provided, the eggs being held in an outwardly inclined position 105 extending from each side of the central partition 27.

The amplitude of the upper arc-shaped edge 32 is very much larger than that of the corresponding edge 11 of the slots 6 and 7 and the supporting edge 33 inclines downwardly to the lower end of this arc-shaped edge instead of inclining upwardly as indicated at 10 in the first described construction, so that the outer partitions are held in a downwardly inclined position instead of an upwardly inclined position as described. 110 120 125 130

From this description it will be seen that I have devised a very simple form of filler which will be simple and cheap to manufacture, which will hold the eggs on a cushioned support which extends around beneath and on one or more sides of each egg, and which is also collapsible; such a filler, moreover, when set up for use within the carton will be rigid so that a person may grip the central wall 12 between the thumb and finger and lift the whole filler, together with eggs contained therein, from the carton for removal to any desired location without danger of the eggs slipping therefrom, the filler thus serving as a medium by which the eggs may be carried from one point to another, the same as though placed in a basket.

The invention may be variously modified, and several examples of alternate construction are set forth in Figs. 6 to 12 to which reference will now be made.

In the example shown in Figs. 6, 7, and 8, the several cross walls 35 are provided with slots which are generally similar in design to the slots 28 and 29 illustrated in Fig. 5. Each slot is formed with an entering portion 36, preferably flared inwardly to provide a narrow gap having adjacent its outer side a shoulder 37. Opposite this shoulder and starting at a slightly higher elevation is a ledge 38 having a slight downward slant. At the inner end of this ledge is formed an arcuate edge 39 which swings around upwardly and outwardly to join a vertical edge 40 which rises from a point adjacent the shoulder 37. This arcuate edge has for its center a point in the region of the gap which lies between the entering slot portion 36 and its enlarged upper portion 41 defined by the ledge 38, arcuate edge 39 and vertical edge 40.

The slot just described is located relatively close to one of the ends of the cross wall and is matched by a second slot, reversed in position, near the opposite cross wall end. Also centrally of each cross wall are two aligned vertical slots 42 and 43 the former extending upwardly from the lower edge for perhaps half the height of the wall. Between these two slots is an intervening body portion 44. The upper slot may be slightly wider than the other for reasons which will presently appear.

Extending through all the cross walls is a central partition 45 having slots 46 cut inwardly from its upper edge at points corresponding to the positions of the several cross walls. Each slot is shown as gently curved for a portion of its length and then straightened out at its lower end where a shoulder 47 in the form of a projecting ratchet tooth is provided. This tooth overhangs the lower straight portion of the slot wherein is received the cross wall body portion 44 lying between the two slots 42 and 43. In bringing the partition into this position relative to the cross

walls, it is necessary to force the latter past the tooth 47 which thereafter prevents casual separation of these parts.

Two other partitions 48 exactly alike are also extended through the several cross walls adjacent the opposite ends thereof. These latter partitions have vertical aligned slots 49 and 50 extending inwardly from their upper and lower edges 51 and 52, respectively, but separated by an intervening body portion 53 which is adapted to rest upon the ledge 38. The opposite edges of the lower slot 50 may also diverge to provide a widened inner end. Such a slot is shown also in Fig. 11. These outer partitions 48 are adapted to swing from a vertical position (as shown by dotted lines in Fig. 6) where they are in parallelism with the central partition 45, through slightly more than 90 degrees to rest their upper edges 51 on the bottom of the carton or container in which the filler is placed. When so positioned, as shown in Fig. 6, these two edges 51 lie close to each other on opposite sides of the central partition, the two outer partitions being inclined slightly toward each other to provide slanting bottoms for the cells between the cross walls. These bottoms, it should be noted, are elevated by the support afforded by the ledges 38 so as to suspend in an elevated position the eggs or other objects contained within the cells.

In swinging to the serviceable position just described, the body portion 53 is guided by the arcuate edge 39 so as to maintain the filler components in their intended relation. In this movement the partition pivots on the shoulder 37. In the initial position wherein all three partitions are parallel, the filler may be collapsed, as suggested in Fig. 7. When fully collapsed, the shouldered side of the entering slot 36 may be received within one of the widened sides of the slot 49. In assembling the outer partitions in place, it is necessary to force the body portion past the shoulder 37 of each cross wall, but when in final position the parts are locked, thereby against separation.

In the use of a filler constructed in accordance with Figs. 6, 7, and 8, the eggs are protected against shocks transmitted through the carton bottom by means of their suspension or cushion support on the partition 48. Should eggs on opposite sides of the central partition vary greatly in size, it is possible for this partition to shift laterally wherever necessary one way or the other within the limits of the widened slots 43. In so doing, the partition will be bent slightly from the position which is determined by its support elsewhere so that each egg will be held firmly between the partition and the outer walls of the carton.

Referring now to Fig. 9, I have shown a cross wall 55 having slots entering at opposite ends adjacent the bottom. Each slot has

a flaring entering portion 56 terminating in a gap at the upper side of which is a shoulder 57. Beyond this gap the slot proceeds with an upper horizontal edge 58 and a lower edge 59 which is downwardly slanted to provide a ledge, these two edges being joined at their inner ends by a vertical edge 60. This cross wall is also formed with a central vertical slot extending inwardly from its upper edge. 10 This latter slot may have a flaring entering portion 61 terminating in a gap at one side of which is a shoulder 62 which overhangs an enlarged inner slot end which is defined by one vertical edge 63 and an arcuate edge 64 extending therefrom laterally and upwardly to the shoulder. The arcuate edge has for its center a point in the region of the gap. 15 Associated with a plurality of cross walls such as has just been described are three longitudinally extending partitions. The central partition 65 is provided with aligned vertical slots extending inwardly from its upper and lower edges and separated by intervening body portions 66 which may be forced 20 past the shoulders 62 to rest in the enlarged inner ends of the central slots in the several cross walls. Due to the widened inner end of these slots last referred to, the body portions 66 are free to swing around through 90 degrees or so when it is desired to move the central partition from a horizontal to a vertical position, or vice versa. The other two partitions 67 which are alike in all respects are interengaged with the lateral slots of the 25 several cross walls. These latter partitions are slotted substantially the same as in the central partition with a body portion 68 intervening between each pair of aligned slots. 30 These body portions may be forced past the shoulders 57 into position adjacent the inner ends of the lateral slots, as indicated in Fig. 9. The outer partitions are then suspended along these outer edges so as to provide a cushion support for eggs which may be confined in the 35 cellular spaces between the cross walls, the central partition, and the vertical walls of the carton (not shown). To collapse this filler the inner edges of the outer partitions are 40 raised until these parts are in horizontal alignment, and the central partition is swung to a horizontal position, as indicated by dotted lines, following which the entire filler 45 may be folded down to occupy a minimum space. 50 In Figure 10 I have further simplified the construction. In this instance each cross wall 69 is provided centrally with a double slot extending inwardly from its bottom edge. The two branches of this slot are disposed 55 along opposite sides of a diamond-shaped tongue 70 which cooperates with projecting shoulders 71 to provide two gaps beyond which are flaring end portions bordered outwardly by vertical edges 72 and inwardly by 60 the slanting edge of the diamond tongue. 65

With cross walls so constructed but two partitions 73 need be employed. These are alike and are adapted for interengagement one within each branch of the double slot just described. Each partition is slotted inwardly from its upper and lower edges in such manner as to provide an intervening body portion 74 (see Fig. 11 also in this construction). The two partitions may stand vertically in parallelism, permitting the filler then to collapse, or slantingly with their upper edges juxtaposed so as to provide a cushion lateral support for eggs in the cellular spaces between the cross walls, the filler being then locked in a rigid condition against collapse. 70 A further construction as disclosed in Fig. 12 remains to be considered. Here the cross walls 69 are double slotted centrally as in the construction last described, in addition to which other vertical slots, similar to the lateral slots of Fig. 9, are provided. These several slots in the construction of Fig. 12 are designated by reference numerals the same as are the portions of the corresponding slots just mentioned. The same applies also to the two central partitions. Two outer partitions 75 additionally are provided, and each is slotted the same as the remaining partitions 73, there being intervening body portions 76 which engage within the outer slots the same as do the corresponding portions 68 of the partitions 67 in the slots of Fig. 9. The four partition construction, as suggested in Fig. 12, provides an outside slanting wall for each cellular space, in addition to an inner slanting wall therefor, the effect being to form V-pockets for the eggs which are suspended above the carton bottom and removed from the outside walls thereof. When all four partitions are straightened up into parallelism the filler may be collapsed, but not otherwise. 90 95 100 105 110 115 120 125

The inventive idea herein disclosed may be expressed in many forms a few of which have been suggested in detail. It comprises in every instance a cellular egg carrier having intersecting components, one set having a swinging mounting relative to the other set such as to permit of a condition of parallelism necessary for folding purposes. One set of these components may also occupy slanting positions in which they are supported by engagement with the other set of components. These several features have already been dwelt upon in the preceding description. Accordingly I desire to be protected to the full extent of the appended claims without regard to details of construction except as therein specified. 110 115 120 125

I claim:

1. A collapsible egg holder or filler comprising a plurality of cross walls, longitudinal partitions extending between the cross walls, and means providing a pivotal engagement between the cross walls and partitions adja- 130

cent the lower edges of the latter to permit swinging of the partitions when in set up position from a vertical position between the cross walls to a slanting position relative to the vertical, whereby to resist collapsing of the holder or filler and provide supporting surfaces for eggs.

2. In an egg holder or filler, a plurality of cross walls each having a slot extending from its lower edge having an enlarged upper end, a partition having a slot extending from its upper edge in alignment with each cross wall, the two sets of slots being interfitting, and the cross walls being so constructed as to provide a pivotal support for the partition whereby the partition may swing from a vertical position to a slanting position relative to the vertical when in set up position, whereby to resist collapsing of the filler and provide supporting surfaces for eggs.

3. A collapsible egg holder or filler, comprising a plurality of cross walls, a plurality of partitions coacting with the cross walls to form egg receiving spaces, engaging means between the cross walls and partitions permitting the walls and partitions to swing from a position at right angles to each other to a parallel or collapsed position, the partitions being so formed as to swing to an angle relative to the vertical, and means when the partitions are swung to such an angle for automatically locking the partitions and cross walls from swinging to a collapsed position.

4. In a filler for egg cartons, a plurality of cross walls each formed with a slot extending from its lower edge and having an enlarged upper end, one edge of the slot being vertical and the upper portion of the opposing edge being inclined outward towards the upper end of the slot to form an enlargement, a partition having a slot extending from its upper edge in alignment with each cross wall, the two sets of slots being interfitting, and a projection extending from the vertical edge of each wall slot to form a pivotal support for the partition in direct longitudinal alignment with the inclined edge of the slot.

5. In a filler for egg cartons, a plurality of cross walls each having a slot extending from its lower edge, one edge of the slot being vertical and the upper portion of the opposing edge being inclined to enlarge the upper end of the slot, a partition having a slot extending from its upper edge in alignment with each cross wall, a ratchet tooth projection extending from the vertical edge of each wall slot in proximity to its lower end having the short arm of the tooth extending horizontally to form a pivotal support for the partition when the latter is swung from the vertical position against the vertical edge of the slot to an inclined position against the opposing inclined edge of the slot.

6. In a filler for egg cartons, a plurality of cross walls each having a slot extending from

its lower edge, one edge of the slot being vertical and the opposite edge being inclined in opposite directions from its ends, a ratchet tooth projection extending from the vertical edge of the slot in proximity to its lower end and having its apex adjacent the apex formed by the inclined edge portions of the opposing side of the slot, a partition having a slot extending from its upper edge in alignment with each cross wall, there being a notch extending from the lower edge of the partition in vertical alignment with each slot, the bases of the notches being adapted to bear upon the horizontal edges of the ratchet notches to permit the partition to swing from a vertical position against the vertical edges of the wall slots to an inclined position against the opposing inclined portions of such slots in which latter position collapsing of the filler is resisted.

7. An egg filler or holder in which is comprised two series of walls in intersecting relation, one set of walls having slots complementary to and coacting with other slots in the second series of walls, the slots of one set being configured to permit independent movement of the walls of the other set from a position in which the lines of intersection are shifted into or out of parallelism and to support said walls in the last named position.

8. An egg filler or holder in which is comprised a plurality of cross-walls upstanding in parallel vertical planes, a pair of partitions intersecting the cross-walls on each side of the center thereof, said partitions being so constructed and connected to the cross-walls as to permit the partitions to be arranged into or out of parallelism, whereby to provide support against collapse of the cross-walls when in said last named position.

9. In a collapsible egg holder or filler which is adapted to collapse without disassembly, a plurality of cross walls, and at least two longitudinal partitions interlocked with the cross walls by interengaging slots and notches, one of said partitions being transversely slotted to straddle the lower portion of the cross walls, whereby said partition may be rearranged relative to another partition in set up position of the filler to provide an egg supporting surface for each cell and to brace the cross walls to resist collapsing of the filler.

10. An egg holder or filler comprising a plurality of cross walls and a plurality of partitions, each cross wall and partition having interlocking engagement with each other, certain of the partitions being transversely slotted to permit intersection therewith of certain portions of the cross walls, whereby a collapsing of the filler is permitted by one arrangement of said partitions, while a second arrangement of said partitions relative to the cross walls provides an egg supporting surface between each cross wall and

a brace for each cross wall to prevent the collapse of the filler.

11. In an egg holder or filler, a plurality of cross walls each provided with laterally spaced apertures, a pair of partitions extending longitudinally of the filler, one adjacent each side edge of the cross walls and being so constructed as to interlock with apertures therein to assume parallel vertical planes in which position of the partitions the filler may be collapsed, said partitions being slotted to swing and straddle a lower portion of each cross wall when swung to provide a slanting egg supporting surface for each cell and to resist collapsing of the filler when in set up position.

12. In an egg holder or filler, a plurality of cross walls each provided with laterally spaced apertures, a central partition extending longitudinally of the filler and having means interlocking with an aperture in each cross wall, and side partitions also extending longitudinally of the filler and arranged adjacent each side edge of the cross walls and being so constructed as to interlock with other apertures therein to assume parallel vertical planes in which position of the partitions the filler may be collapsed, said side partitions being transversely slotted to swing and straddle a lower portion of each cross wall to each side of said central partition when swung to provide a slanting egg supporting surface between each cross wall and to provide a brace for each cross wall to prevent collapse of the filler when in set up position.

13. In a collapsible egg holder or filler, a plurality of cross walls each formed with laterally spaced irregular slots extending inwardly from the lower edge thereof and providing lateral projections partially obstructing each slot, and a plurality of partitions each formed to interlock with the irregular slots of the cross walls and pivot upon the lateral projections, the slots of the cross walls being so shaped as to permit independent swinging movement of the partitions relative to the cross walls, whereby said partitions may be swung on their pivots from a vertical position, in which position the holder or filler may be collapsed, to a slanting position to resist collapsing of the holder or filler and provide supporting surfaces for eggs.

14. An egg holder or filler comprising, a plurality of egg supporting cells formed by one set of parallel strips in intersection with another set of parallel strips, one set of parallel strips being so formed as to be movable relative to the other set of parallel strips to assume vertical or slanting positions, and being spaced apart at their connection with the other set of parallel strips a distance slightly less than the width of eggs to be accommodated within the cells, whereby upon introduction of an egg into a cell the receiving edges of the two movable strips

will be shifted away from each other to turn such strips into slanting positions with converging portions of the strips remote from the receiving edges engaging the egg to sustain the same from below upon opposite sides thereof.

Signed at Chicago, this 18th day of May, 1928.

JOSEPH LEOPOLD COYLE.
